US00D674893S

(12) **United States Design Patent**
Kinsey et al.

(10) **Patent No.:** US D674,893 S
(45) **Date of Patent:** ** Jan. 22, 2013

(54) **INHALER DEVICE**

(75) Inventors: **P. Spencer Kinsey**, Sandy Hook, CT (US); **Benoit Adamo**, Mount Kisco, NY (US)

(73) Assignee: **MannKind Corporation**, Valencia, CA (US)

(**) Term: **14 Years**

(21) Appl. No.: **29/404,464**

(22) Filed: **Oct. 20, 2011**

(51) **LOC (9) Cl.** 24-04

(52) **U.S. Cl.** D24/110; D24/110.5

(58) **Field of Classification Search** D24/108-110, D24/110.4, 110.5; 128/200.14-200.23, 203.12-203.24

(57) **CLAIM**

The ornamental design for an inhaler device, as shown and described.

DESCRIPTION

FIG. 1 is a front perspective view of an inhaler device of our design.

FIG. 2 is a rear perspective view of the inhaler device of FIG. 1.

FIG. 3 is a bottom perspective view of the inhaler device of FIG. 1.

FIG. 4 is a top view of the inhaler device of FIG. 1.

FIG. 5 is a bottom view of the inhaler device of FIG. 1.

FIG. 6 is a first side view of the inhaler device of FIG. 1.

FIG. 7 is a second side view of the inhaler device of FIG. 1.

FIG. 8 is a front view of the inhaler device of FIG. 1; and,

FIG. 9 is a rear view of the inhaler device of FIG. 1.

The broken lines immediately adjacent the shaded areas represent the bounds of the claimed design while all other broken lines are directed to environment and are for illustrative purposes only; the broken lines form no part of the claimed design.
